4 Claims. (Cl. 340—172.5)

The invention relates to a device for the automatic ascertainment of an interruption in a sequence of successively incoming serial numbers, which device comprises two registers, in each of which a number can be stored, a comparison member which is capable of ascertaining whether the numbers stored in the two registers are equal or unequal, this member producing, in the case of inequality, a signal in an adder capable of raising by one the number stored in the second of the two registers, provision being made of means to transfer an incoming serial number to the first of the two registers.

Such devices may be used, for example, in automatic telegraph systems. The telegrams transmitted via a channel are provided with a serial number. The serial numbers constitute a running sequence of numbers in which each serial number exceeds normally by one the preceding serial number.

At the receiver end of the transmission channel the telegrams are received in the order in which they are transmitted. The serial number of an incoming telegram is, consequently, normally higher by one than the serial number of the previously received telegram.

The second register of the known device comprises a digit equal to the serial number exceeding by one of the previously received telegram. When a new telegram is received its serial number is compared with the said number. If equality is stated, the telegram can be sent to the desired outlet channel. The known device produces a signal, when inequality is stated. Then the transmission of the new telegram is postponed until a supervising operator has taken down the serial number of the new telegram and the number stored in the second register. These two numbers indicate the end and the beginning respectively of the interruption in the sequence of incoming serial numbers. Then the operator again actuates the comparison member.

It should be noted that in the known device the number stored in the second register is raised by one after the comparison of the numbers. For practical reasons it may be preferable to augment the number by one after the reception of the new serial number in the first register and to compare subsequently the numbers stored in the two registers. In this method the number stored in the second register is equal to the last-received serial number. For the invention it is unessential which of the two methods is employed.

The known device has a disadvantage in that the delay occurring in the transmission of a received telegram to the desired outlet channel may be great.

The invention has for its object to obviate this disadvantage.

The device according to the invention comprises to this end means to transfer an incoming serial number to the second register, whilst the assembly is such that the incoming of the serial numbers produces signals which actuate successively the comparison member, the last-mentioned transfer means and the adder in the following order: comparison member—transfer means—adder—comparison member—transfer means—adder, it being immaterial whether the signal produced by an incoming

2

serial number actuates the comparison member or the adder, the device comprising furthermore a third register and a fourth register, in each of which a number can be stored, means to transmit a number stored in the first register to the third register, means to transmit a number stored in the second register to the fourth register, which means become operative by the comparison member subsequent to the ascertainment of inequality and finally a bistable member, of which the two states are designated by 0 and 1 and which is moved into the state 1, when inequality is stated by the comparison member, whereas the means for the transmission of a number stored in the second register to the fourth register do not become operative when the bistable member occupies the condition 1.

The invention will be described more fully with reference to an embodiment shown in the drawing.

FIG. 1 shows one embodiment.

FIG. 2 shows the translation circuit arrangement employed.

FIG. 3 shows a 2-out-of-5 code.

The serial numbers of telegrams or a different sequence of numbers, in which normally each number exceeds by one the preceding number, are supplied in order of succession to the input terminals $G_1 \dots G_{10}$ of a register RG_1 , shown in FIG. 1.

The numbers are coded in a given manner, for example in accordance with a 2-out-of-5 code. For a number of two digits ten code elements are required, which correspond to the input terminals $G_1 \dots G_{10}$. The presence of a code element is indicated by the connection of the corresponding input terminal to earth.

If at the input terminals $G_1 \dots G_{10}$ the code elements of a number occur, the relays $A_1 \dots A_{10}$, connected to these input terminals are energized. After a relay has been energized, it closes a holding circuit for itself via a make contact of the relay and the common break contact *au*.

The incoming number is supposed to be the first serial number. In this case the registers RG_3 and RG_4 have the number 00 and the register RG_2 may have, for example, the number 01.

In the translation circuit TS the number 02 is formed. The circuit TS may be a generally known translation circuit. A particular embodiment thereof is described more fully hereinafter. This circuit comprises ten relays $T_1 \dots T_{10}$, which are energized via the contact network KN . The translation circuit is shown in detail in FIG. 2. In FIG. 3 is indicated the coding of the numbers employed. With reference to this figure the operation of the translation circuit can be understood in a simple manner. The term "adder" used in the claims is to be understood to denote such a translation circuit.

If, for example, the register RG_1 has the number 12, it is evident from FIG. 3 that the relays A_1 , A_3 and A_7 , A_{10} are energized. A cross-hatched square indicates that the code element concerned is present. The topmost sequence of numbers indicates the decades of the number of the code element and the sequence of numbers below the former indicates the number of the code element for the units.

From FIG. 2 it follows that the relays T_1 , T_3 and T_6 , T_9 are energized. This relay combination corresponds to the number 13, which appears from FIG. 3.

If a number ending in the digit 9 is stored in the register RG_1 , the relays A_8 and A_9 are energized. The translation circuit includes a relay H , which is energized by the series combination of the make contacts a_8 and a_9 . The translation circuit increases the decade of the number stored in the register RG_1 by one via the change-over contacts h . If this number is, for example, 19, the relays A_1 , A_3 and A_8 , A_9 are energized. From FIG. 2 it ap-

pears that the relay H and the relays T₂, T₅ and T₇, T₈ are energized. This relay combination corresponds to the number 20.

In the embodiment the numbers consist of two digits, which are coded in accordance with a 2-out-of-5 code. However, the invention is not restricted thereto. The circuit may be adapted in a simple and known manner to numbers having more than two digits and to other codes.

Simultaneously to the formation of the number 02 by the translation circuit TS, the relay U is energized via at least one of the make contacts a₁ . . . a₁₀. In the number comparison circuit VS the numbers stored in the registers RG₁ and RG₂ are compared with each other. This circuit comprises, in the manner shown, a change-over contact of each of the relays A₁ . . . A₁₀ and B₁ . . . B₁₀.

In the case under consideration the registers RG₁ and RG₂ have the same number, i.e. the number 01. The corresponding relays in the two registers are energized.

Between the conductor N₂, which is connected to the change-over contacts b₁ . . . b₁₀, and the conductor N₁, which is connected to the change-over contacts a₁ . . . a₁₀, no conductive connection is established. However, a conductive connection is established, if a change-over contact connected to the conductor N₂ is changed over and the corresponding change-over contact connected to the conductor N₁ is not changed over and conversely. In the latter case there is inequality between the numbers stored in the registers RG₁ and RG₂. This inequality is signalled by the lifting of relay FC. The energizing circuit is as follows: negative voltage, winding relay FC, make contact U, conductor N₁, at least one of the change-over contacts a₁ . . . a₁₀, the corresponding change-over contacts of the group b₁ to b₁₀, the conductor N₂, break contact gc, make contact U, earth.

After relay FC has been energized, it closes a holding circuit for itself via the make contact fc and the break contact au. The energizing circuit of the delayed relay GC is interrupted by the break contact fc. Relay GC can then not be lifted.

When the registers RG₁ and RG₂ have the same numbers, no conductive connection is established between the conductors N₁ and N₂ and the relay FC cannot be lifted. This equality is signalled by the lifting of relay GC. The energizing circuit is as follows: negative voltage, winding relay GC, break contact fc, make contact U, earth. After relay GC has been energized, it closes an individual holding circuit via the make part of the change-over contact gc and the break contact au.

A break contact of the relay GC opens the holding circuit of the relays in the register RG₂, so that the energized relays are deenergized. After the deenergization of these relays relay P is energized via the series combination of the break contacts b₁ . . . b₁₀. This relay closes an individual holding circuit via the make contacts p and gc. The make contacts p₁ . . . p₁₀ of relay P connect the outputs of the translation circuit TS to the corresponding inputs of the register RG₂. In the register RG₂ the number 02 is stored. After the relays in the register RG₂ have been energized, they close an individual holding circuit via the individual make contact and the common make contact p. Relay AU is energized via the series combination of the make contacts p and gc. After relay AU has been energized, the relays in the register RG₁ and relay GC are deenergized. After the deenergization of these relays the relays in the translation circuit TS, relay U, relay AU and the relay P are deenergized.

The register RG₂ then registers the number 02. If no interruption occurs in the sequence of numbers fed to the register RG₁, the subsequent number supplied is the number 02. This number is compared with the number 02 stored in the register RG₂ and then raised by one to be supplied to the register RG₂. Then the register RG₂ has the number 03 and so forth.

The telegrams transmitted through a channel receive

a serial number which is always higher by one than the telegram sent before. The first telegram, which is supposed to be sent after midnight receives the serial number 01. The last telegram sent prior to midnight has a high serial number, for example the serial number 95.

5 The number stored in register RG₂ will therefore be the number 96. When the number 01 is fed to the register RG₁, the comparison member VS ascertains inequality between this number and the number stored in the register RG₂. In the manner described above relay FC is energized. After the relay FC has been lifted, the break contact fc opens the holding circuits of the relays in the registers RG₃ and RG₄. The numbers stored in these registers get lost.

10 15 After the relays C₁ . . . C₁₀ in register RG₃ have been deenergized, relay R is energized via the series combination of the break contacts c₁ . . . c₁₀. Relay R closes a holding circuit for itself via the make contacts r and fc. The outputs of the register RG₁ are connected via the 20 make contacts r₁ . . . r₁₀ of relay R to the inputs of the register RG₃. Via these make contacts the number stored in the register RG₁ is fed to the register RG₃. The relays in the register RG₃, which are energized, close a holding circuit for themselves via their individual make contact 25 and the common make contact r. The number stored in this register is in this case the number 01.

25 30 After the relays D₁ . . . D₁₀ in the register RG₄ have been deenergized, relay S is energized via the series combination of the break contacts d₁ . . . d₁₀. The outputs of the register RG₂ are connected via the make contacts s₁ . . . s₁₀ of relay S to the inputs of the register RG₄. In the register RG₄ those relays are energized which correspond with the energized relays in register RG₂. The number stored in register RG₄ is in this case 35 the number 96. After the relays D₁ . . . D₁₀ are energized, relay S is deenergized. In the meantime the winding of the polar relay K has been connected via the make contact s to the negative terminal of a battery B and thus brought into the operational position. The 40 change-over contact k closes with the make side of the contact a holding circuit for the relays D₁ to D₁₀ in register RG₄ and opens by its break side the holding circuit of the relays B₁ . . . B₁₀ in register RG₂. In the manner described above the number formed in the translation circuit TS, in this case the number 02, is fed to the register RG₂ and stored herein. Then the relay AU is energized via the series combination of the make contacts p, r and fc. After relay AU is lifted, the circuit is moved into the rest position in the manner described and in 45 this case also the energized relay R is deenergized.

50 55 In a manner not shown the relay FC governs a monitoring device. When the monitoring device is actuated, this is an indication for the operator that inequality has been stated.

55 The outputs of the registers RG₃ and RG₄ may, for example, be connected, in a manner not shown, via translation circuits, to a digit dial. After the occurrence of the alarm the operator can verify in a simple manner the numbers stored in the said registers.

60 65 In the present case the registers RG₃ and RG₄ have the number 96 and the number 01 respectively. These numbers provide the operator with the information that the last serial number received before midnight is the serial number 95 and that a new sequence of serial numbers has started.

65 70 The operator then actuates the push-button DT. This button connects the winding of the polar relay K to the positive terminal of the battery B. Thus the relay goes over to the rest position.

70 75 In the holding circuit of the relays D₁ . . . D₁₀ in register RG₄ the break contact fc is no longer shunted by the change-over contact k. On the contrary the change-over contact k shunts the break contact fc in the holding circuit of the relays B₁ . . . B₁₀ in register RG₂.

If no interruptions occur in the new sequence of serial

numbers, the arrangement operates in the manner described above, so that the new serial number, raised by one, is stored in register RG₂.

If an interruption occurs in the sequence of serial numbers, since one or more serial numbers have not been received, the number stored in register RG_2 , corresponding with the first, non-received serial number, will, as described above, be transferred to the register RG_4 and the new incoming serial number will be transferred to the register RG_3 . At the same time relay K is brought into the operational condition and an alarm is given.

The serial numbers subsequently received are worked up in the manner described above. The numbers in the registers RG_3 and RG_4 remain stored herein.

If again an interruption occurs in the sequence and if relay K is in the operational position, the holding circuit of the relays $B_1 \dots B_{10}$ in the register RG_2 is interrupted after relay FC has been lifted. The relays $D_1 \dots D_{10}$ in register RG_4 remain energized.

As described above, the register RG_2 has fed to it the number formed in the translation circuit TS . The register RG_3 receives the new serial number.

Owing to the energization of relay AU the arrangement is brought into the rest position.

The number stored in the register RG_4 continues indicating the first, non-received serial number. The number stored in register RG_3 is the first serial number received after the second interruption.

When, after an alarm, the operator actuates the push-button DT, a new interruption of the sequence of serial numbers is completely registered by the registers RG₃ and RG₄.

and RG₄.

1. A system for detecting the interruption of a sequence in sequentially occurring input signals, said system comprising first, second, third and fourth registers, a source of said input signals, signal comparison means, an adder, means applying said input signals to said first register and to said adder, said adder adding a predetermined signal to said input signal, means applying signals stored in said first and second registers to said comparison means, means responsive to the detection of an equality in said comparison means for clearing said first and second registers and for applying the output of said adder to said second register, means responsive to the detection of an inequality in said comparison means for transferring the signals in said first and second registers to said third and fourth registers respectively, for clearing said first and second registers, and for applying the output of said adder to said second register, and reset means for inhibiting subsequent transfer of signals from said second register to said fourth register while permitting subsequent transfer of signals from said first register upon the detection of a subsequent inequality in said comparison means.

2. A system for detecting the interruption of a sequence in sequentially occurring input signals, said system comprising first, second, third and fourth registers an adder for adding a predetermined signal to said input signal, signal comparison means comprising first control means responsive to an equality between signals applied thereto and second control means responsive to an inequality between signals applied thereto, first circuit means for

transferring signals from said first register to said third register, second circuit means for transferring signals from said second register to said fourth register, third circuit means for transferring signals from said adder to said second register, means applying said input signals to said first register and adder, means for comparing signals of said first and second registers in said comparison means, said first control means being connected to permit transfer of signals by way of said third circuit means, and to clear said first and second registers said second control means being connected to permit transfer of signals by way of said first, second and third circuits and to clear said first and second registers, and reset means for inhibiting transfer of signals by way of said second circuit but permitting transfer of signals by way of said first circuit subsequent the detection of a first inequality in said comprising means.

3. A system for detecting the interruption of a sequence in sequentially occurring input signals, said system comprising first, second, third and fourth registers, and adder for adding a predetermined signal to said input signal, signal comparison means having first and second relay means responsive to equality and inequality respectively of signals applied to said signal comparison means, first contact means for transferring signals from said first register to said third register, second contact means for transferring signals from said second register to said fourth register, third contact means for transferring signals from said adder to said second register, means applying said input signals to said first register and said adder, means for comparing the signals of said first and second registers in said comparison means to selectively operate said first and second relay means, said first relay means having first and second contacts connected to clear said first and second registers, and third contacts connected to close said third contact means for a predetermined time upon the detection of an equality, said second relay means comprising fourth, fifth and sixth contacts connected to close said first, second and third contact means, and seventh and eighth contacts connected to clear said first and second registers and reset means for inhibiting the closing of said second contact means while permitting the closing of said first contact means upon the detection of a second inequality in said comparison means.

45 4. The system of claim 3 in which said first, second and third contact means are contacts of third, fourth and fifth relay means respectively, said fourth contacts being connected to clear said third register and energize said third relay means, said fifth contacts being connected to clear said fourth register and energize said fourth relay means, and said third and sixth contacts being connected to energize said fifth relay means.
